(57) **CLAIM**

The ornamental design for an aromatic nebulizing diffuser, as shown and described.

DESCRIPTION

FIG. 1 is a perspective view of a partially transparent aromatic nebulizing diffuser embodying the design;

FIG. 2 is a front view of a partially transparent aromatic nebulizing diffuser embodying the design shown in FIG. 1;

FIG. 3 is a rear view of a partially transparent aromatic nebulizing diffuser embodying the design shown in FIG. 1;

FIG. 4 is a left side view of a partially transparent aromatic nebulizing diffuser embodying the design shown in FIG. 1;

FIG. 5 is a right side view of a partially transparent aromatic nebulizing diffuser embodying the design shown in FIG. 1;

FIG. 6 is a top plan of a partially transparent aromatic nebulizing diffuser embodying the design shown in FIG. 1; and

FIG. 7 is a bottom view of a partially transparent aromatic nebulizing diffuser embodying the design shown in FIG. 1;

FIG. 8 is a perspective view of a second embodiment of an aromatic nebulizing diffuser embodying the design;

FIG. 9 is a front view of an aromatic nebulizing diffuser embodying the design shown in FIG. 8;

FIG. 10 is a rear view of an aromatic nebulizing diffuser embodying the design shown in FIG. 8;

FIG. 11 is a left side view of an aromatic nebulizing diffuser embodying the design shown in FIG. 8;

FIG. 12 is a right side view of an aromatic nebulizing diffuser embodying the design shown in FIG. 8;

FIG. 13 is a top plan of an aromatic nebulizing diffuser embodying the design shown in FIG. 8; and,

FIG. 14 is a bottom view of an aromatic nebulizing diffuser embodying the design shown in FIG. 8.

The broken lines shown in the drawings are for illustrative purposes only and form no part of the claimed design.
